Primary Examiner — Raphael Barkai(74) *Attorney, Agent, or Firm* — Sheridan Ross P.C.**CLAIM**

The ornamental design for eye glasses, as shown and described.

DESCRIPTION

FIG. 1 is a front elevation view of eye glasses showing my new design;

FIG. 2 is a rear elevation view thereof;

FIG. 3 is a left elevation view thereof;

FIG. 4 is a right elevation view thereof;

FIG. 5 is a partial perspective detail view of FIG. 4;

FIG. 6 is a top plan view thereof;

FIG. 7 is a bottom plan view thereof; and,

FIG. 8 is a perspective view thereof.

The broken lines of some figures are for illustrative purposes only and form no part of the claimed design.
